TAPE EMBOSsing TOOL

John H. Humphrey, Los Angeles, and Harry F. Scheirer
and Leonard W. Cheslak, Garden Grove, Calif., assign-
ors to Apsco Products, Los Angeles, Calif., a corpora-
tion of Illinois, a division of Maple Industries, Inc.

Filed Jan. 12, 1967, Ser. No. 5,401

Term of patent 14 years

(Cl. D64—10)

FIG. 1.

FIG. 2.

FIG. 3.

FIG. 4.

FIG. 5.

FIG. 6.

FIG. 1 is a top plan view of a tape embossing tool showing our new design;

FIG. 2 is a side elevational view of FIG. 1;

FIG. 3 is a front end view of FIG. 2;

FIG. 4 is a bottom plan view of FIG. 1;

FIG. 5 is an elevational view showing the side opposite to that of FIG. 2; and

FIG. 6 is a rear end view of FIG. 2.

The essential features of the design reside in the portions shown in solid lines.

We claim:

The ornamental design for a tape embossing tool, substantially as shown and described.
